UNITED STATES PATENT OFFICE.

WILLIAM G. MILLER, OF BROOKLYN, NEW YORK.

PIN-ATTACHING MACHINE.

Application filed June 21, 1923. Serial No. 646,966.

To all whom it may concern:

Be it known that I, WILLIAM G. MILLER, a citizen of the United States, residing at Brooklyn, in the county of Kings and State 5 of New York, have invented certain new and useful Improvements in Pin-Attaching Machines, of which the following is a specification.

The present invention relates to clincher 10 devices for the pins of pin attaching machines, and consists in the combinations and arrangements of elements hereinafter described and particularly set forth in the accompanying claims.

15 In the usual type of pin attaching machines provision is made for bending the prongs of the pins inwardly or outwardly but to effect this it becomes necessary to place on the machine the particular form 20 of clincher device desired to be used, and this obviously requires the mechanical interchanging of the clincher devices with the attendant trouble incident thereto and loss of use of the machine during the interim.

25 To avoid these objections the present invention proposes to provide an attachment so constructed and mounted on the machine that by simple and quick operation the machine may be set to bend the prongs inwardly or outwardly, and this without in 30 any manner reconstructing the machine or appreciably altering its present arrangement.

The duplex clincher device disclosed herein 35 is designed with a special reference to the Soabar type of pin ticketing machine though it will be understood that the mechanism employed and its principle of operation are adapted to any type of pin attaching machine wherein the pins are capable of having their prongs bent inwardly or outwardly.

The invention is disclosed by way of illustration in the accompanying drawing, 40 wherein:

Figure 1 is a side elevational view showing the device installed on a Soabar pin ticketing machine;

Fig. 2 a top plan view thereof;

50 Fig. 3 a transverse sectional view taken on the line 3-3 of Fig. 1;

Fig. 4 a detail perspective view of the duplex clincher device per se;

55 Fig. 5 a transverse sectional view of the duplex clincher device taken on the line 5-5 of Fig. 4;

Fig. 6 a detail view of the shifting key;

Fig. 7 a detail view of the eccentric mounted on the shifting key, and

Fig. 8 a detail view of the shifting key 60 lock.

Referring to the construction in further detail and wherein like reference characters designate corresponding parts in the different views shown, 9 represents the base 65 or frame portion of the Soabar machine; 10 the pin slide thereof; 11 the pin bender arm; 12 the lever for operating pin bender arm 11; 13 the pin clincher arm; and 14 the lever for operating said arm.

70 The lever 12 is provided with the usual bracket piece 15 carrying spring tensioned bolt 16 engaging with the bifurcated member 17 that operates the pin bender arm 11; and within the trough portion of said arm 11 is fulcrumed, at 18, the clincher arm 13. Said pin bender arm 11 is in turn fulcrumed on the stem 19 of the key member 20 journaled in the bed portion 9 of the machine (see Fig. 2).

75 The duplex clincher device per se consists of a block member 21 detachably secured to the end portion 22 of the bender arm 11 by the pair of screws 23, or in any other approved manner. Said block 21 is recessed in 80 its upper portion, as at 24, to receive the prongs of the ticket pins and bend the same inwardly after the manner of the special form of clincher for effecting this and with which the Soabar pin ticketing machine is 85 equipped.

The block 21 carries the outward clincher device in the form of a plate 25 centrally cut away (see Fig. 4) and mounted to have limited movement within the pair of opposed slots 26 formed in opposite sides of the clincher block 21, as shown. A slot 27 formed in the lower end of the clincher member 25 receives the end member 28 of the clincher arm and it is thereby operated 90 through the instrument of the pair of levers 12 and 14, as will be understood.

95 The means for shifting the duplex clincher device consists of an eccentric member 29 mounted on the stem 19 of the key 20 and fitting within a corresponding shaped opening formed in the fulcrum end of the pin bender arm 11. Said eccentric member and the key 20 are held against relative rotation by a pin 30 on the key stem 110 19 engaging within a slot 31 formed in the eccentric (Figs. 6 and 7). It will therefore

be seen that by turning the key member 20 the respective clincher devices are moved into and out of operative position.

The locking device for holding the key 20 in set position consists of a latch piece 32 slidably fitted on the base portion 9 by the two screws, one acting as spring anchor, 33 engaging in slots 34, of the latch piece, and a retraction spring 35 engaging the latch handle 36 normally holds the end 37 of the latch piece in locking engagement with the stem 19 of the key 20.

The operating lever 12 is provided with the usual adjusting and jam nuts 38 and 39 for raising or lowering the pin bending arm; and in like manner the clincher operating lever 14 is fitted with adjusting nuts 40, as shown.

It is obvious that those skilled in the art may vary the details of construction and arrangement of parts without departing from the spirit of the invention, and, therefore, I do not wish to be limited to such features except as may be required by the claims.

25 What is claimed as new is:

1. In a pin attaching machine the combination of devices for applying pins having prongs, a duplex clincher adapted for movement in one direction to shift the clincher devices, and a member movable in another direction to carry the duplex clincher into operative position, substantially as set forth.

2. In a pin attaching machine the combination of means for applying pins having prongs, a pair of clincher devices for bending the pin prongs inward or outward, an arm on which said clincher devices are mounted, and a device for shifting said arm to bring either of said clincher devices into operative position, substantially as set forth.

3. In a pin attaching machine the combination of means for applying pins having prongs, a pair of clincher devices for bending the pin prongs inward or outward, an arm on which said clincher devices are 45 mounted, and an eccentric element for shifting said arm to bring either of said clincher devices into operative position, substantially as set forth.

4. In a pin attaching machine the combination of means for applying pins having prongs, a pair of clincher devices for bending the pin prongs inward or outward, an arm on which said clincher devices are mounted, a device for shifting said arm to 50 bring either of said clincher devices into operative position, and a locking element associated with said arm, substantially as set forth.

5. In a pin attaching machine the combination of means for applying pins having prongs, a block having elements for bending the pin prongs inward or outward, a fulcrumed arm on which said block is mounted, and an eccentric device for shifting the 55 arm to bring either of the clincher devices of the block into operative position, substantially as set forth.

6. In a pin attaching machine the combination of means for applying pins having prongs, a block constructed to bend the pin prongs inward, a member slidably mounted on said block for bending the pin prongs outward, and devices for shifting the 70 block and said slideable member into their respective operative positions, substantially as set forth.

In testimony whereof I affix my signature.

WILLIAM G. MILLER.
